OIL BURNER NOZZLE

Filed Nov. 5, 1927

FIG-1

FIG-2

INVENTOR
Charles L. Rayfield
By *Charles L. Rayfield* Atty's

UNITED STATES PATENT OFFICE

CHARLES L. RAYFIELD, OF CHICAGO, ILLINOIS, ASSIGNOR TO RAYFIELD MANUFACTURING COMPANY, A CORPORATION OF ILLINOIS

OIL-BURNER NOZZLE

Application filed November 5, 1927. Serial No. 231,183.

My invention relates in general to nozzles, spark rods or electrodes 20. The points 21 of these spark rods 20 are positioned to one side of the discharge orifice of the nozzle 10. That is to say, the spark is emitted from these electrodes above the path of the fuel discharged from the nozzle 10. Obviously the air discharged from the pipe or sleeve 18 into the hood 13 will force the spark into the fuel jet emanating from the nozzle 10. I shall now proceed to describe in detail the construction of my novel nozzle 10.

5 The object of the present invention is to provide an improved oil burner nozzle adapted to impart a whirling action to the fuel discharged therefrom, thus enabling the fuel to be thoroughly atomized.

10 Other objects and advantages of my invention will more fully appear from the following detailed description taken in connection with the accompanying drawing, which illustrates a single embodiment thereof and in which:

Figure 1 is a fragmentary sectional view partly in elevation illustrating the nozzle of my invention as part of an oil burner;

20 Figure 2 is a view partly in section and elevation of my nozzle illustrating in detail the construction thereof;

Figure 3 is an enlarged end view of the grooved member of my nozzle;

25 Figure 4 is a side elevation partly in section of the member shown in Figure 3, and

Figure 5 is a cross-sectional view taken on substantially the line V—V of Figure 4 looking in the direction indicated by the arrows.

In the drawings:

30 Like reference characters designate similar parts throughout the several views.

The reference character 10 designates generally the nozzle of my invention, which is shown in Figure 1 as being connected to a

35 threaded member 11 which constitutes part of the oil line 12. The nozzle 10 (Figure 1) is disposed within a semi-spherical hood 13 having a Venturi-shaped discharge orifice 14. It will be noted that the nozzle 10 is

40 normally positioned within the discharge orifice 14 of the hood 13. The tubular member 11 is supported within the hood 13 by means of an extension 15 rigidly fastened to the hood 13 at 16. The hood 13 includes a

45 tubular portion 17 telescoped by an airpipe or sleeve 18 which is adapted to be secured to the portion 17 through the means of the set-screw 19.

Extending through the air tube 18 and into

55 one side of the discharge orifice of the nozzle 10. That is to say, the spark is emitted from these electrodes above the path of the fuel discharged from the nozzle 10. Obviously the air discharged from the pipe or sleeve 18 into the hood 13 will force the spark into the fuel jet emanating from the nozzle 10. I shall now proceed to describe in detail the construction of my novel nozzle 10.

60 The nozzle 10 includes two cooperating tubular members 23 and 24. Member 24 comprises a reduced threaded end 25 adapted to be threaded into the tubular member 11, an intermediate hexagonal or nut portion 26, and a threaded portion 27 adapted to be screwed into a threaded opening 28 in member 23. Extending through the member 24 is a passageway 29 which terminates at one 65 end in an enlarged or flared opening 30 formed by countersinking one end of the threaded portion 28.

70 The member 23, in addition to the threaded opening 28, has a somewhat smaller opening 31 in which is disposed a grooved member 32. This member 32 abuts one end of the portion 27 of member 24 and at its other end abuts the end portion 33 of member 23. The end portion 33 has a central opening 34 75 which comprises the discharge orifice of the nozzle 10.

75 Now it will be evident that the member 24 may be readily disconnected from the member 23 by gripping the hexagonal or nut portion 26 by a suitable wrench and unscrewing the threaded portion 27 from the member 23. Moreover, after the member 24 has been disconnected from the member 23, the grooved member 32 may be removed from the member 23 through its enlarged or threaded opening 28.

80 The construction of the grooved member 32 is clearly shown in Figures 3, 4 and 5. This member merely comprises a part of a 85 cylindrical rod. This member 32 is provided with a plurality of spiral teeth or flutes 35, preferably four in number, on its outer periphery. These flutes are separated by spiral grooves 36.

The operation of my nozzle is briefly as follows:

The oil or other fuel upon leaving the pipe 12 passes through the tubular portion 11 into the passageway 29 in member 24. This fuel is discharged from the passageway 29 into the flared opening 30 which allows the fuel to enter the spiral grooves 36. The pressure of this fuel entering the grooves 36 is of sufficient force to cause the member 32 to impart a whirling action to the fluid. This whirling of the fuel results in the atomization of the liquid fuel or oil prior to its leaving the discharge orifice 34 of the nozzle 10.

This whirling fuel is forced into contact with the relatively sharp edge 33' of end portion 33 of member 23, which cuts or breaks up the fuel, thus resulting in a more complete atomization of the fuel. The fuel upon leaving the nozzle 10 is discharged into the stream of air leaving the hood 13 and is ignited by the spark of the electrodes 21.

Now, of course, it is to be understood that although I have illustrated and described in detail the preferred form of my invention, the invention is not to be thus limited, but only in so far as defined by the scope and spirit of the appended claim.

I claim as my invention:

30. In combination, in a nozzle, a tubular member including a fuel discharge orifice defined by a relatively sharp edge, a second member connected to and extending into said tubular member and having a fuel passageway, said second member including a flared discharge orifice disposed in communication with said fuel passageway, and a member mounted in said tubular member abutting said second member adjacent said flared orifice, said latter member including a spiral groove disposed at one end in communication with the outer periphery of said flared orifice and at its other end with the discharge orifice in said tubular member, said flared orifice serving to direct the fuel into said spiral groove and said spiral groove serving to atomize the fuel, said edge of the tubular member being beveled inwardly toward and in substantial alignment with the bottom of said spiral groove so as to cut the whirling fuel as it leaves said groove.

In testimony whereof I have hereunto subscribed my name at Chicago, Cook County, Illinois.

35

CHARLES L. RAYFIELD.
